UNITED STATES PATENT OFFICE.

ROBERT SMITH DICKINS, OF ENTERPRISE, FLORIDA.

BOAT PROPELLING AND STEERING MECHANISM.

SPECIFICATION forming part of Letters Patent No. 656,692, dated August 28, 1900.

Application filed October 30, 1899. Serial No. 735,251. (No model.)

To all whom it may concern:

Be it known that I, ROBERT SMITH DICKINS, a citizen of the United States, residing at Enterprise, in the county of Volusia and State 5 of Florida, have invented a new and useful Boat Propelling and Steering Mechanism, of which the following is a specification.

The invention relates to boat propelling and steering mechanism.

10 The object of the present invention is to improve the construction of boat propelling and steering mechanism and to provide a simple and comparatively-inexpensive construction designed to be applied to an ordinary boat for the purpose of dispensing with oars or sails and other propelling devices and adapted to be operated similar to an ordinary bicycle and capable of developing a high rate of speed.

20 The invention consists in the construction and novel combination and arrangement of parts hereinafter fully described, illustrated in the accompanying drawings, and pointed out in the claim hereto appended.

25 In the drawings, Figure 1 is a plan view of a boat provided with propelling and steering mechanism constructed in accordance with this invention. Fig. 2 is a longitudinal sectional view of the same. Fig. 3 is a transverse sectional view on the line 3-3 of Fig. 2. Fig. 4 is a detail perspective view of the seat-frame and the steering-post. Fig. 5 is a detail perspective view of the bearing of the propeller-shaft. Fig. 6 is a detail sectional view illustrating the manner of stepping the steering-post.

Like numerals of reference designate corresponding parts in all the figures of the drawings.

30 1 designates a propeller-shaft disposed longitudinally of the rear portion of a boat 2 and extending through the stern thereof and carrying at its rear end a propeller 3, which is arranged between the rudder 4 and the stern of the boat, the latter being provided with a recess or inwardly-offset portion to provide a space for the propeller. The rudder has a straight inner edge, and it is hinged contiguous to the stern of the boat at the top 45 and bottom of the same, and by providing the recess at the lower portion of the stern the propeller is arranged in advance of the plane

of the same and does not interfere with the operation of the rudder or necessitate the same being offset from the stern of the boat. 55 The propeller is of the ordinary construction, and the propeller-shaft, which is disposed at a slight inclination, is journaled in a bearing 5, consisting of a substantially V-shaped frame provided at its top or apex with a bearing-opening 6 and having the lower terminal 7 of its sides bent upward at an angle and perforated for the reception of suitable fastening devices for securing it to the sides of the boat. The front end of the propeller-shaft carries a pinion 8, which meshes with a gear-wheel 9, having spur-teeth on one of its faces and mounted on a crank-shaft 10, which is journaled in suitable bearings 11 of a fork 12 of a seat-frame 13. The lower ends 60 14 of the sides of the fork are bent upward, similar to the terminals 7 of the sides of the bearing, in order to enable them to be readily attached to the opposite sides of the boat, and the extreme lower portions of the sides of the 70 fork are bent outward to form diverging portions 15. The crank-shaft is provided at its ends with suitable pedals 16 and the gear-wheel 9 has spokes 17 and 18, the spokes 18 being enlarged to provide the necessary 75 weight and to balance the wheel. The pedals are adapted to be actuated by the feet of the operator and the boat is propelled similar to an ordinary bicycle, as will be readily apparent, the rotation of the gear-wheel 9 causing 80 a rotation of the propeller 3.

The seat-frame 13 is preferably constructed of tubular metal, and it supports an ordinary bicycle-seat 19 and is connected by a horizontal brace or bar 20 with a vertical steering-post 21, provided with handle-bars 22 and having its lower end 23 stepped in a bearing 24. The bearing 24 consists of a block or plate provided with a socket and having suitable perforations for the reception of fastening devices for securing it to the bottom of the boat. The steering-post is supported, near its lower end, by a substantially V-shaped bearing 25, constructed similar to the bearing before described, with the exception that 90 the bearing-opening 26 is arranged vertically. The front end of the horizontal bar or brace 20 is provided with a bearing 27 to receive the upper portion of the steering-post, and

the latter is provided at its lower portion with laterally-extending arms 28, preferably formed by a rod arranged in a perforation of the post and provided at its ends with eyes 29. The eyes of the arms 28 have the front or forward ends of tiller ropes or cords 30 attached to them, and these tiller ropes or cords extend rearward to the stern of the boat and are suitably secured to a cross-bar or tiller 31, which is centrally mounted on the upper end of the rudder-post 32.

The operator sits in the saddle 19 and propels the boat with his feet, operating the pedals similar to an ordinary bicycle, and he is enabled to steer the boat by means of the handle-bar 22, which is arranged within easy reach. The tiller ropes or cords, which extend from the arms 28 to the tiller, are guided by suitable pulleys 33, arranged at opposite sides of the boat, as clearly illustrated in Figs. 1 and 2 of the accompanying drawings.

It will be seen that the steering and propelling mechanism, which is simple and comparatively inexpensive in construction, possesses great strength and durability, that it is adapted to be readily applied to any ordinary small boat, and that it is capable of being operated as easily as an ordinary bicycle. It will also be apparent that the mechanism is compactly arranged and does not take up much of the space of the boat, that it is adapted to be arranged close to the bottom of the boat, and that it does not necessitate a high structure which might render a small boat top-heavy and unstable. Furthermore, it will be clear that as the power is applied directly to the propeller-shaft friction is reduced to a minimum and a maximum speed may be obtained.

What is claimed is—

In a device of the class described, the combination of a boat provided at the lower portion of its stern with an inwardly-extending recess, the upper portion of the stern being arranged at a slight inclination, a rudder having an inclined inner edge fitting against the inclined upper portion of the stern and connected to the latter at the top and bottom thereof, the forked standard provided with diverging lower portions and having upturned outwardly-inclined terminals secured to the boat at opposite sides thereof, a steering-post located in advance of the standard, the horizontal brace 20 connecting the upper portions of the standard and the post, the substantially V-shaped front bearing supporting the lower portion of the post and having upturned inclined terminals secured to the sides of the boat, the V-shaped rear bearing provided at its apex with a bearing-opening and having upturned inclined terminals secured to the boat, the propeller-shaft arranged in the rear bearing and extending through the lower portion of the stern of the boat and provided with a propeller located in the said recess, a crank-shaft journaled in suitable bearings of the forked portion of the standard, gearing connecting the shafts, and connections between the rudder and the steering-post, substantially as described.

In testimony that I claim the foregoing as my own I have hereto affixed my signature in the presence of two witnesses.

ROBERT SMITH DICKINS.
